UNITED STATES PATENT OFFICE.

OTTO GROSS, OF LONGSIGHT, MANCHESTER, ENGLAND.

ELECTRIC-ARC LAMP.

No. 851,003.

Specification of Letters Patent.

Patented April 23, 1907.

Application filed December 20, 1904. Serial No. 237,689.

To all whom it may concern:

Be it known that I, Otto Gross, a subject of the Emperor of Germany, of The Otto Electrical Manufacturing Company, Limited, 5 residing at 504 Stockport road, Longsight, Manchester, in the county of Lancaster, England, electrical engineer, have invented certain new and useful Improvements in Electric-Arc Lamps, (for which I have made an 10 application for patent in Great Britain, No. 21,242, dated October 4, 1904,) of which the following is a specification.

My invention relates to electric-arc lamps, and particularly arc striking mechanism.

15 Under this invention I utilize carbons carried in tubes which converge one toward the other, the arc extending between the approaching extremities, as is known.

I now proceed to describe my invention in 20 detail and with the help of the annexed sheets of drawings, first pointing out the nature of the figures in the drawings.

Figure 1 is a vertical elevation, partly in section, of a converging carbon-lamp. Fig. 25 2 shows an elevation of the lamp at right angles to the position in Fig. 1. Fig. 2^a shows a detail. Fig. 3 is an enlarged explanatory view of the lower part of the lamp and shows the carbons, moving tubes, and clutches, the 30 latter having clutched the carbons and retracted same. Fig. 4 is also an enlarged explanatory view similar to Fig. 3, but with the clutches disengaged and showing the carbons entirely released and resting on the 35 arc-ing plate.

In lamps according to this present invention I preferably use converging carbon-tubes *a b* and I arrange for such converging tubes or part thereof to slide or reciprocate or to be 40 deflected angularly, either movement serving my purpose. In the lamp shown in the drawings the converging tubes *a b* have telescopic portions *a' b'*, which slide upon or within the upper portions of the carbon-tubes *a b*. Upon the tubes *a' b'* the clutches C C are arranged, and these are so designed as to grip the carbons and retract same and move with them until the carbons are released by disengagement of the clutches. 45 The clutches C C (shown in the drawings) consist of small eccentrics or cams or disks *d d*, which are pivoted at points *d' d'* to small clip or other brackets *e e*, which clip the slide- 50 able tubes *a' b'*, or are otherwise secured thereto. These eccentrics or cams *d d*, of which there are two to each carbon, (see

Figs. 2 and 2^a), have preferably a milled or serrated periphery slightly concaved, and they are disposed in jaws in the brackets *e e* opposite slots *a²*, formed in the tubes *a' b'*, 6c (see Fig. 3,) so as to be able to bear on each carbon at two points at the required times for the purpose of gripping same. Each eccentric or cam *d d*, pivoted at the points *d' d'*, is jointed at the points *d² d²* by small pivot-pins or otherwise to links *f*, which are in turn adjustably connected to a cross-head, such as *g*, which cross-head may have horns or extensions *g'*, which, embracing the tubes *a b*, assist in guiding such cross-head in its 70 up-and-down movements.

When the cross-head *g* is raised, it pulls the links *f*, which turn each eccentric or cam *d d* on its pivots *d' d'* and force a part of the periphery of the eccentrics or cams into contact 75 with the carbons, so that the carbons are held. Immediately the carbons are gripped or clutched the eccentrics and clip-brackets *e e* begin to rise, and with them the tubes *a' b'*, 80 which telescope within the other tubes *a b*, and so the carbons are retracted. When the cross-head and the link attachment begin to fall, the telescopic tubes *a' b'* and brackets fall too, and with them the clutches gripping the carbons, the whole of the parts falling 85 bodily, and this takes place until the lower edges of the tubes *a' b'* encounter the base of the lamp or other abutments, such as *i i*. Upon this occurring the further descent of such tubes is arrested and the weight of the 90 cross-head, links, and connected parts is thrown on the pivot-pins *d² d²*, and so the eccentrics are turned downward upon their pivots *d' d'*, and in this manner the gripping portions of the eccentrics are moved away 95 from contact with the carbons, which are consequently released and fall onto the arc-ing plate A.

The way in which the cross-head, such as *g*, is controlled may vary considerably; but I 100 prefer to work by means of one or more solenoids or coils or by a combination of solenoids or coils. In the Figs. 1 and 2 I have shown the cross-head *g* connected to a movable and adjustable core *h*, (having a dash-pot *h'*,) 105 the action of the core being governed by a coil *i*. The coil *i* shown consists of a "series coil" *s* with a superimposed "shunt-coil" *s'*. The action of such coil *i*, core *h*, and arrangement of mechanism is as follows: When the 110 current is first switched on, the series coil *s* is strongly energized and sucks up the core *h*

and cross-head g , and this latter in turn acts on the links marked f and causes same to pull the eccentrics into contact with the carbons, which are now firmly clutched, so that with 5 the further ascent of the core the whole of the parts move upward together. (See more particularly Fig. 3.) Thus the carbons are retracted and the lamp kept burning. As consumption of the carbons take place the 10 shunt-coil s' becomes a little stronger and (being oppositely wound) neutralizes the series coil s , and so the core falls a little, and consequently the whole of the moving parts appertaining to the carbons. As soon as the 15 shunt-coil s' becomes sufficiently strong to neutralize the series coil s to such an extent as to allow the core and cross-head g to fall sufficiently to permit the tubes $a' b'$ to encounter the abutments $i i$ (see Fig. 4) the eccentrics release the carbons. (See Figs. 1 20 and 4.) When this occurs, the carbons immediately fall onto the arcing plate A, whereupon the series coil again sucks up the core and the carbons are clutched and retracted. 25 I arrange that when the carbons are released the arcing-plate A shall be always below in a position to receive them, and for this purpose I work such arcing plate from the cross-head, so that the position of the cross-head governs the position of the arcing-plate. 30 In the drawings an adjustable extension or turnbuckle k from the cross-head g works a link l , acting on a bell-crank lever m , pivoted at m' to a fixed bracket n , and this bell-crank 35 lever m is connected by a swivel o to a pin on the arm p , which works the vertical rod q , carrying the arcing plate A. The vertical

rod is carried in a bearing r on the base of the lamp. The construction of the parts is such that every movement of the cross-head affects 40 the arcing plate to some extent, and when the downward movement is sufficient to bring the sliding tubes against the abutments then the arcing plate is immediately below the carbons, just as when the carbons are retracted it is at once swung clear. 45

The current entering the lamp may pass through a blow-magnet j (used to keep the flame a good shape) and then to the positive tube a and across to the negative tube b and 50 thence through the series coil to the negative terminal, the shunt-coil s' being simply connected across.

Though I have described certain means for controlling the feeding of the carbons, I do 55 not claim such means, as any other suitable means may be used for this purpose

I declare that what I claim is—

In combination with arc-lamps having converging carbon-tubes, a moving arcing plate 60 upon which the carbons fall, a connection from the cross-head, a turnbuckle, a link, a bell-crank lever, a swivel connection and an arm, and a bearing for the arcing-plate support, said arcing plate being constantly and 65 correspondingly influenced by a movement of the core.

In witnesses whereof I have hereunto set my hand in presence of two witnesses.

OTTO GROSS.
